UNITED STATES PATENT OFFICE.

WILLIAM W. GREEN, OF NILES, MICHIGAN.

AUTOMATIC REGULATOR FOR CARBURETERS.

1,110,131.

Specification of Letters Patent.

Patented Sept. 8, 1914.

Application filed November 10, 1913. Serial No. 800,085.

To all whom it may concern:

Be it known that I, WILLIAM W. GREEN, a citizen of the United States, and a resident of Niles, county of Berrien, and State of Michigan, have invented certain new and useful Improvements in Automatic Regulators for Carbureters, of which the following is declared to be a full, clear, and exact description.

0 This invention relates to carbureters for internal combustion engines and designs to provide means for automatically regulating the flow of gasolene through the carbureter. Those skilled in this art are aware that a 15 greater flow of gasolene is required to start gasolene engines in cold weather than in warm weather, and much difficulty is encountered in adjusting the carbureter so that the proper flow of gasolene may be had. 20 This regulation of the flow is usually controlled by a needle valve, and it is practically impossible to reset the valve after it has been adjusted to permit a larger flow, so that much annoyance and engine trouble is occasioned.

25 The primary object of this invention is to provide means for automatically adjusting the needle valve of the carbureter, which means receives its action from the changes 30 of temperature.

To such end this invention consists in the several novel features hereinafter set forth and claimed.

The invention is clearly illustrated in the 35 accompanying drawing in which:—

Figure 1, is a side elevation of a fragment of a motor vehicle, the engine and its carbureter, and showing one form of the present invention applied thereto; Fig. 2, is 40 a detail cross section taken on line 2—2, Fig. 1; and Fig. 3, is a plan of a needle valve stem, a crank thereon and a valve actuating member.

45 Referring to said drawings, 10 designates an engine, of the internal combustion type, 11 the hood, 12 the radiator, and 13 the dash of a motor vehicle; 14 designates the intake pipe of the engine, and 15 the carbureter, which may be constructed in accordance 50 with any of the well known forms embodying a needle valve 16, having a needle valve stem or spindle 17, screw threaded in a support 18, and arranged to regulate the flow of gasolene through the carbureter. By 55 screwing it down toward its seat, less gasolene is admitted, and by unscrewing it, more

gasolene is admitted with the air to form the required mixture or charge for the engine. In warm weather the passage through this needle valve is closed more than in cold 60 weather, and this adjustment has heretofore been done manually and more or less imperfectly.

In my novel automatic regulating mechanism, one or more readily expandible and 65 contractible members 20, 21, 22, are employed, which are supported within the hood 11, and one member of which is connected to the needle valve spindle of the carbureter, as, for instance, by a crank 23. In the form 70 shown I provide two supports 24, 25 for the members 20, 21, 22, which members are here shown as comprising rods, preferably constructed of brass, so as to obtain a long range expansibility, and said supports 75 are shown as secured to the dash 13, and radiator 12, respectively. One end of the rod 20, is secured to a lug 26, on the support 24, and its other end is pivotally secured to one end of a lever 27, fulcrumed, between its 80 ends, on an arm 28, of the support 25. To the other end of the lever 27, is pivotally secured one end of the second rod 21, whose other end is pivotally secured to one end of a second lever 29, fulcrumed between its 85 ends, upon a lug 30, of the support 24. One end of the third rod 22, is pivotally secured to the other end of the lever 29, and its other end is pivotally secured to the end of the crank 23. A set screw 31, threaded in the 90 crank and bearing on the needle valve stem or spindle, provides means for adjustably connecting the crank with the stem. By arranging the fulcrums of the levers 27, 29, as shown, the rod attached to the long end of 95 each lever is moved bodily through a greater distance than the one attached to the short arms of the levers, consequently through the expansion and contraction of the rods the crank 23, may be moved sufficiently to properly operate the needle valve stem.

The arm 28 of the support 25, is preferably of light construction, so that it may yield when the rods have been subjected to the temperatures radiating from the engines 105 when running, and have been expanded sufficiently to turn the needle valve stem far enough to cut down the flow of gasolene, when the engine is running. The yieldable arm permits further expansion of the rods 110 without affecting the valve, and an adjustable connection 32, is provided between the

arm 28, and lever 27, for properly setting the rods in position.

In adjusting the regulator, the set screw 31, is screwed back from the needle valve 5 stem 17, of the carbureter, and said stem is then adjusted to permit the proper flow of gasolene through the carbureter.

The crank occupies a position, dependent on the action of the rods thereon, and when 10 the needle valve stem has been adjusted to place, the set screw is screwed down tight against the stem. When the engine is started and heat is developed within the hood, the rods expand, the rod 20, swinging the 15 lever 27, and moving the rod 21, onward, which, because of its expansion, in addition to the movement imparted to it by the lever 27, swings the lever 29, through a greater arc than the lever 27, and this movement is 20 again multiplied in the expansive movement of the rod 22, whereby the crank 23, is turned sufficiently to move the needle valve stem closer to its seat and thereby reduce the flow of gasolene through the carbureter. A stop is provided for limiting the 25 valve closing action of the rods at the proper point, and in the form shown, the lever 29, strikes the support 24, at such time. Any further expansion of the rods is taken up by 30 the arm 28, of the support 25.

From the above it will be seen that the needle valve is opened considerably on a cold day, by reason of the contraction of the rods when the engine is not running, 35 thereby admitting more gasolene through the carbureter when the engine is being started, and that when started and heated up the valve is closed down to the proper place. On a warm day the valve is automatically closed more than on a cold day, 40 by reason of the expansion of the rods, thus admitting less gasolene than on a cold day, when starting the engine and when the engine has started and is heated up, the ex-

panding rods close down the valve to its proper running order as before.

More or less variation is possible without departing from the spirit of this invention and I desire therefore not to limit myself to the exact form of the invention shown 50 and described, but intend in the following claims to point out all of the invention disclosed herein.

I claim as new and desire to secure by Letters Patent:—

1. Means for automatically regulating needle valve-controlled carbureters for internal combustion engines of motor vehicles, comprising a plurality of contractible and expansible rods, one of which has a fixedly 60 supported end, motion multiplying levers connecting said rods and a crank on the needle valve stem, connected to and operated by the rod farthest removed from the rod having the fixed end.

2. Means for automatically regulating valve-controlled carbureters for internal combustion engines, comprising expansible and contractible members, one of which has a fixed end, operative connections therebetween, a stop for limiting movement of said members in one direction, and a connection between one of said members and the controlling valve of the carbureter.

3. Means for automatically regulating valve-controlled carbureters for internal combustion engines, comprising a plurality of contractible and expansible rods, one of which has a fixed end, throw increasing levers for said rods, one of which is carried 80 by a yieldable support, a stop for limiting the movement of said rods, and an operative connection between the last one of said rods and the valve of the carbureter.

WILLIAM W. GREEN.
